UNITED STATES PATENT OFFICE.

REINHOLD BOEKLEN AND JOHN D. AVERELL, OF BROOKLYN, NEW YORK.

APPARATUS FOR GENERATING ILLUMINATING-GAS.

SPECIFICATION forming part of Letters Patent No. 324,809, dated August 25, 1885.

Application filed October 29, 1884. (No model.)

To all whom it may concern:

Be it known that we, REINHOLD BOEKLEN and JOHN D. AVERELL, both citizens of the United States of America, and residents of the 5 city of Brooklyn, in the county of Kings and State of New York, have invented a new and useful Improvement in Apparatus for Generating Illuminating-Gas, of which the following is a specification.

10 This invention relates to apparatus for generating illuminating-gas by the successive operations of superheating and decomposing steam, vaporizing oil, or producing oil-gas in one or more chambers separate from the fuel, 15 mixing the water-gas resulting from the decomposed steam with the oil gas and vapor, and subjecting them to contact with heated material in the mixing and fixing chamber, all in one structure; and the invention consists in novel features of construction and in 20 certain combinations of parts, hereinafter described, and particularly pointed out in the claims.

We provide the generating furnace or cupola with vertical inwardly-projecting steam-superheaters composed of fire-tile and inclosed steam-pipes, the latter connecting at their lower ends with inclined steam-nozzles projected inwardly and upwardly, and having at 25 their outer ends drip-pipes, sight-cocks, and clearing and inspection tubes. We also construct in the upper part of the generator, in contact with the side walls thereof, inwardly-projecting oil-gas-generating chambers having tile shelves, oil-supply nozzles, and passages connecting with the fuel-chamber and with the mixing-chamber of the cupola, whereby the oil-gas for carbureting or enriching the water-gas is generated without subjecting the oil to 30 contact with the fuel, thus avoiding waste and loss of oil so often caused by its conversion into lamp-black. We also construct a mixing and fixing chamber extending across the top of the cupola, having a perforated bottom connecting with the fuel and steam-decomposing chamber and with the oil-gas-generating chambers, and having a filling of lime and a gas-outlet pipe.

In the drawings hereto annexed, Figure 1 35 represents a vertical central section of the cupola or gas-generator constructed accord-

ing to our invention. Fig. 2 is a horizontal section of the same, taken at its top mixing-chamber. Fig. 3 is a similar section of the same, taken below said chamber above the 55 cold space of the cupola. Fig. 4 is a detached vertical lateral section of one of the oil-gas-generating chambers.

The lower end of this cupola is built with a cylindrical and flanged castash-pit case, A, having a cast bottom bolted to its bottom flange. To its top outward flange is jointed and bolted the bottom flange of the cupola-shell B, and it has on this top also an inward flange to support the trunnions of its grate C', and to support the lining of the interior of the shell. The ash-pit is also lined with fire-brick, and has the sealed door D for removing the ashes, and has attached the blast-pipe E, provided with air-valve F for stopping the blast. The top 7c end of the shell B has a flange, to which is jointed and bolted the cupola metal top plate or cover, G. Through the top and cover G is provided the coal-inlet H and also the gas-outlet I. Over the grate is arranged a suitable 75 coal-space, J, and above it is a space, K, for fixing the water-gas. The top is built with a large mixing-chamber, L, formed of fire brick and tile. Along the lining of the cupola are arranged several alternately-distributed vertical steam-superheaters, M, and vertical oil-gas-generating chambers N, of semicircular form, built of fire-tile and protruding from the lining.

O represents the oil-supply pipe, from which 85 the oil is distributed to the several oil-gas chambers N, and is in each introduced by the oil nipples or nozzles P P.

Q represents the steam-supply pipe, from which the steam is distributed to the several 90 steam-superheaters by the branch pipes R, and is injected into the coal-space and fire by means of the steam nipples or nozzles S S.

From the water-gas chamber K are several openings T into the chamber L, and the bottom portions of the chambers N have also 95 openings T', for passing the water-gas into the chambers N. The nozzles S S and their lining protrude considerably into the coal-space J, to cause the steam to impregnate the coal and 100 not to pass along the cupola-lining.

The superheaters are constructed each with

a strong vertical steam-pipe, *a*, which is connected at its top end with the branch pipe *R* by a horizontal pipe, *b*, passing through a stuffing-box on the shell of the cupola. Each 5 branch pipe *R* is furnished with a stop-valve, *c*, to regulate the supply. The bottom end of the pipe *a* connects with the lateral steam-nozzle *S*, which has a short end, *d*, projecting into the opening in the tile to the coal-space, and 10 has a long end, *e*, passing out through a stuffing-box attached to the shell of the cupola, and has attached a small drip-pipe, *f*, with a drip-valve, *g*, and on its extreme end is furnished a sight-cock, *h*.

15 To carry the condensation of the steam out from the cupola, the nipples *S* are inclined downward and outward toward their drip-pipes *f*. By opening the sight-cock *h* the heat of the fire is readily inspected in blowing up 20 the fire, and by inserting a rod through the nozzle and said cock the steam-passage is readily opened and cleared from cinders. The top of the pipe *a* has a plug extending through the top plate to withdraw said pipe *a* 25 for repairs. Said top plate is furnished with the cap *i* to cover the pipe *a*. The chambers *N* connect at their top ends with the mixing-chamber *L*, and they are made with lateral alternate projecting shelves *N'*, to form a zig- 30 zag passage and cause the oil-vapor to rub the incandescent tile surfaces, and thereby effect the proper fixing of the oil-gas. Each oil-nozzle *P* has a cock, *j*, to regulate its oil-supply, and has, similar to the nozzles *S S*, a 35 plug-cock, *k*, in line with its opening, for passing the cleaning-rod through the nipple and clearing the same from soot or other obstructions, and also for inspection of the heat in the chamber *N*. The bottom end of each chamber 40 *N* is provided with a small sealed man-hole, *N''*, to provide for cleaning said chamber from ashes.

The chamber *L* is furnished with lime for purifying the gas. Over the gas-outlet *I* is 45 provided the *T*-pipe *V*, from which the gas is conducted by the pipe *V'* to the gas-main or wash-box. Said *T*-pipe *V* has a hinged cover or seal, *W*, provided with a lever-arm, *l*, on the outer end of which is suspended the pull-rod *m*, for operating said cover from the 50 cupola-floor. The coal-inlet *H* is furnished with a mouth-piece, *Y*, and also with a hinged cover or seal, *Z*, having a lever-arm, *n*. A secondary two-armed lever, *o*, is employed in 55 a standard, *p*, attached to the top plate, *G*, for operating the cover *F*, for which purpose the arm *n* is connected with the short arm *q* of the lever *o*. The long arm, *r*, of the lever *o* has suspended to it the pull-rod *s*, for 60 operating and raising the cover *F* after the gas is generated and delivered, and before the air-blast is started into the cupola. The joints of both covers *F* and *W* have a peculiar novel construction to provide for tight, reliable, 65 and quick opening and closing of them at the cupola-floor, to avoid the loss of gas and danger of explosion during the generation of the

gas, and to prevent the operatives from burning themselves. Said joints are made conical with the convex portion formed on the 70 cover, and provided with an annular groove, *t*, containing asbestos packing, and the seats for the covers are properly turned concave to conform to the covers. A secondary seal is provided for each cover by an annular groove, 75 *u*, formed around the seat, and containing sand, and by an exterior rim, *v*, formed on the cover to dip into and be sealed by the sand. The usual construction of said covers with ground joints frequently fails to be tight 80 on account of their change by the heat. The grate *C* is constructed of several sections, *C' C'' C'''*, together covering the circular space of the ash-pit. They are made in sections for the purpose of more readily operating, and to 85 permit the replacement of either of them and passing it through the door *D*. Each section has the usual lateral grate-bars, which are secured by a rim at their ends, and each end is furnished with a central trunnion, *w*, 90 on which the section is turned for dumping the grate. For each trunnion is provided a bearing-box attached to the inner flange of the base *A*, and for each sectional grate is located below it a lateral shaft, *x*, which has 95 one or more cranks, *y*, upon it, and its grate-section has suitable lugs, with which said cranks are connected by the links *z*. Said shafts *x* have each one end supported in a suitable bearing attached to the inner side of the case 100 *A*. The opposite end of each shaft protrudes through the side of the base *A* and passes through a stuffing-box attached to the base, and the extreme end of the shaft is furnished with a lever or wrench suitable for vibrating 105 or turning the shaft, and thereby shaking or dumping the relative grate-section.

All steam-supply pipes are furnished with pipes and valves for discharging all steam-condensation.

To generate the gas, the cupola is filled with coal nearly two-thirds of its space from the grate to its interior top, and the coal is made incandescent, and the fire raised to a high heat by assistance of the blast. The drips 115 and valves *g* are allowed to exhaust all steam-condensation. After the superheaters *M* and chambers *N* are properly heated, the covers *Z* and *W* are dropped, and thereby the cupola 120 is closed. The steam and oil supply valves are now opened. The highly-heated steam passes from the nipples *S S* into the coal, which decomposes the same, and the hydrogen, making rapidly, rises and becomes fixed in the space *K*, from which it enters through 125 the openings *T* into the mixing-chamber *L*; at the same time the oil passing through the oil-nipples *P P*, entering the chambers *N*, at once vaporizes, and in contact with the incandescent sides of the chambers and the 130 shelves *N'* soon becomes fixed oil-gas, which rises into the chamber *L* and becomes mixed with the hydrogen gas, and both pass off through the gas-outlet *I*. The top plate, *G*,

has a man-hole properly furnished with the yoke and clamp-screw for ready opening to renew the lime in the chamber L whenever required.

5 What we claim as our invention, and desire to secure by Letters Patent, is—

1. In a gas-generator, the coal-chamber J, having grate G, and the chamber L, in combination with the vertical projecting steam-superheaters M, the connected protruding steam-nozzles inclined inwardly and upwardly, and the drip-pipes f, connected with their outer ends, substantially as and for the purpose described.

15 2. In combination with the water-gas generator having steam-nozzles S, the vertical projecting oil-gas-generating chambers N, secured to the side walls of the furnace and having oil supply nozzles P, substantially as and for the purpose described.

3. In combination with the generating cupola having coal-inlet H and gas-outlet I, the top mixing and fixing chamber, L, having perforations T, leading into the water-gas chamber, 25 and the connecting oil-gas generators N, substantially as and for the purpose herein set forth.

4. The generating cupola having the vertical projecting tile M, provided with passages 30 extending from the top of the cupola to the tuyere-passages, in combination with the inclosed steam-pipes a, having a plug extending through the top plate of the cupola and the protecting-caps i, for the purpose described.

35 5. The combination, with the water-gas generator, the steam-nozzles S, the top mixing-

chamber, L, having passages T, of the vertical inward-protruding oil-gas-generating chamber or chambers N, located above the grate and having oil-nipples P, substantially as and for 40 the purpose herein stated.

6. The cupola gas-generator having coal-chamber J, fixing-chamber K, coal-inlet H, and gas-outlet I, in combination with the steam-superheaters M and their nozzles S, 45 having drip-pipes f, the mixing-chamber L, and the oil-gas-generating chambers N, having oil-nozzles P, for the purpose described.

7. The combination of the protruding steam-superheater M, the branch pipe R, having 50 valve c, the vertical steam-pipe a, with the inwardly and upwardly inclined and protruding nozzle S, having drip-pipe f, and the sight-cock h, substantially as and for the purpose herein described and shown.

8. The cupola gas-generator having coal-chamber J, mixing-chamber L, having passages T, and gas-outlet I, in combination with the oil-gas-generating chamber N, provided with shelves N', forming a zigzag passage, and 60 oil-supply nozzles P, substantially as and for the purpose described.

In testimony that we claim the foregoing as our invention we have signed our names, in presence of two witnesses, this 20th day of 65 October, 1884.

REINHOLD BOEKLEN.
JOHN D. AVERELL.
